United States Patent Office

Des. 193,130
Patented July 3, 1962

193,130

BILLBOARD

Donald O. Wilcox, Fort Pierce, Fla., assignor to General Development Corporation, Miami, Fla., a corporation of Florida

Filed June 8, 1961, Ser. No. 65,521

Term of patent 14 years

(Cl. D1—12)

FIG. 1.

FIG. 2.

FIG. 3.

FIG. 4.

I claim:

The ornamental design for a billboard, as shown.
